UNITED STATES PATENT OFFICE.

MARTIN L. BOWDEN AND MARTIN L. BOWDEN, JR., OF BROOKLYN, NEW YORK.

DESIGN FOR A RING OR SIMILAR ARTICLE.

44,513.

Specification for Design.

Patented Aug. 19, 1913.

Application filed December 2, 1912. Serial No. 734,630. Term of patent 7 years.

To all whom it may concern:

Be it known that we, MARTIN L. BOWDEN and MARTIN L. BOWDEN, Jr., citizens of the United States, and residents of Brooklyn, in the county of Kings and State of New York, have invented a new, original, and ornamental Design for Rings or Similar Articles, of which the following is a specification, reference being had to the accompanying drawing, forming part thereof.

The figure shown is a perspective view of the ring.

We claim:—

The ornamental design for a ring or similar article, as shown.

MARTIN L. BOWDEN.

MARTIN L. BOWDEN, JR.

Witnesses:

LOUIS J. GESTWICK,

W. H. SWENARTON.
